ELECTRICAL MEANS AND METHOD OF
REMOTE CONTROL

Philip Norman Smith, Melrose, Mass.

Application October 5, 1933, Serial No. 692,355

28 Claims. (Cl. 178—27)

This invention relates to a method and means for the remote control of electrical circuits and more particularly to those cases where it is desired to control a large number of circuits at a distance in the simplest possible manner.

It is the object of the present invention to provide such a method and means and also to provide a new method and means for the transmission over short or long distances and by wire or radio means of typewritten characters or the like.

In the accompanying drawings

Figure 1 is an elementary schematic diagram to illustrate the functioning of one part of my invention;

Figure 2 is a modification of the schematic wiring diagram shown in Figure 1;

Figure 3 shows a wiring diagram of a remote control circuit for direct current operation;

Figure 4 shows a detail drawing of the short-circuiting contact;

Figure 5 shows still another modification of my invention;

Figures 6 and 7 show other modifications of the system;

Figure 8 shows a detail of the selector bar de-pressor;

Figure 9 shows a diagram of the essential features of a modification of my invention for transmitting teletype messages using direct current;

Figure 10 shows a detail of the keybar selector switch;

Figure 11 shows the same system as Figure 9 but modified to use alternating currents for radio and long wire circuits which will hereinafter be described in detail.

More particularly this invention utilizes the ability of two electrically controlled and pivotally connected pantograph arms of assuming at their common point, a relation with respect to some other fixed point which is determined by the currents supplied to them, to select for energization one or more of a number of electrical circuits at the will of the operator, from the point from which the controlling currents are sent.

The increasing use of methods for controlling industrial operations from a distance without the necessity of an operator being actually present at the point at which the operations are taking place, is sufficient proof that there is a definite place in industry for a simple apparatus which will make possible the control of a number of operations from a distance. Obviously the number of such operations which can be controlled from a distance with little or no increase in the complexity of the equipment will be a measure of its utility.

The distant control of electrical generating plants and substations, the remote control of radio transmitters, radio ship beacons and aviation beacons, the teletype by means of which typewritten characters can be transmitted to and reproduced at a distant point, are a few examples of the diverse fields in which remote control equipment finds a place.

Some of the methods known to the art for the remote control of the above services involve the transmission, by wire or radio means and if the number of conductors or circuits between the two points is to be kept to a minimum, of a series of impulses of various lengths or groupings which impulses or groups are transformed through some selecting means into the action which it is desired to produce. Thus in the so-called "five unit" teletype system the various characters required in transmitting typewritten messages are obtained by various combinations of impulses in the "five unit" group.

Meter readings and so forth from power stations are transmitted to a control point by various methods some of which involve the use of impulses, some the use of different frequencies and so on. All of these methods become cumbersome however when any great number of operations are to be controlled. There is therefore a distinct demand for a control equipment flexible enough to cover a large number of operations with no added complexity in itself on that account and which does not depend on accurate timing, a large number of control frequencies, impulses or circuits for its positive and accurate action.

This invention meets these requirements in a simple and effective fashion as the following explanation of its operation will show.

In order to understand the principle of this invention reference should be made to the diagram shown in Figure 1. In this diagram 1 is a source of electrical power and maintains a constant voltage across the rheostats 2 and 3. 4 and 5 are short electrically conducting arms of two bell cranks the longer arms of which (6 and 7) are pivotally connected to the rigid arms 8 and 9 which arms are also pivotally joined at their other ends at a common point 10.

It will be clear from the above that as the common point 10 is moved to various points on the tablet 11, the voltages between ground and the conducting arms 4 and 5 of the bell cranks which make contact with the rheostats 2 and 3, will vary depending upon the position of the junction point 10 on the tablet 11.

Suppose now that at some other point which

will be designated as the receiving station, a similar pair of bell cranks are provided and which also have pivotally interconnected rigid arms.

Suppose also that the shorter arms of this second pair of bell cranks are pivotally connected to movable coils 14 and 15 disposed in the magnetic fields provided by the magnets 16 and 17, instead of to the rheostats as was the case at the transmitting station.

10 Suppose further that the varying voltages between the bell crank conducting arms and ground at the transmitting station are carried by wires 12 and 13 to one end respectively of coils 14 and 15 while the other ends of these coils are connected to ground.

The varying voltages set up between wire 12 and ground and between wire 13 and ground will cause correspondingly varying currents to flow through coils 14 and 15 respectively and, since 20 these coils are supported in the permanent magnetic fields provided by the magnets 16 and 17 they will assume a position which will depend upon the magnitudes of the currents traversing them. The movements of these coils 14 and 15 will as a consequence cause movements in arms 18, 19, 20, and 21 with the final result that the 25 common point 22 of rigid arms 20 and 21 will execute with respect to tablet 23 the same movements that common point 10 in the transmitter 30 executes with respect to its tablet 11. Thus if the operator at the transmitting station wishes to have the juncture point 22 assume some position as A on the tablet 23 it will only be necessary for him to move the common point 10 at the transmitter to the corresponding position A' on the transmitter tablet 11 and the desired position A will be automatically achieved.

Similarly if he wishes to have point 22 assume other position such as B or C it can be automatically accomplished by moving point 10 to the corresponding positions B' and C' on tablet 11.

It will be clear from the above that point 22 can be made to assume any desired position on the tablet 23 by moving point 10 to the corresponding 45 position on tablet 11. It will also be clear that the actual mechanical movement of point 10 and the simultaneous movement of arms 4 and 5 on the rheostats 2 and 3 on this account in order to bring about changes in the position of point 22 50 are unnecessary, providing that voltages corresponding to the desired position of 22 are transmitted to coils 14 and 15.

In other words it is possible to have point 22 assume any one of a number of positions on 55 tablet 23 without the necessity of using a similar pantograph system at the transmitter, by providing means for obtaining and transmitting to coils 14 and 15 the voltages needed to make point 22 assume the desired position.

60 Figure 2 illustrates a method of doing this. Resistors 24, 26, 28, 30, 32 and 34 are connected in series across a source of voltage 1 and similarly resistors 25, 27, 29, 31, 33 and 35 are also connected in series across the source of voltage 1. 65 The values of the resistors are so chosen that when the contacts of switch 36 are closed the voltages applied between ground and wire 12 and between ground and wire 13 are such as to cause currents to flow in coils 14 and 15 which will 70 assure that point 22 will assume position A for instance on tablet 23.

Similarly when switch 37 is closed the voltages applied between ground and wire 12 and between ground and wire 13 may be made such as to cause 75 currents to flow through coils 14 and 15 which will

ensure that point 22 will assume position B for instance on tablet 23.

It will be understood that although only six positions of point 22 are shown the same method can readily be extended to include as many positions as may be desired by providing the additional necessary resistors and switches.

Figures 3 and 4 indicate how the above described methods for moving point 22 to any desired position can be utilized in a practical circuit selector. Tablet 23 in Figure 3 can conveniently take the form of a horizontally disposed panel of some insulating material such as Bakelite. At points A, B, C, D, E, and F are provided pairs of electrically conducting segments which are 15 supported by the panel 23.

Furthermore an insulated piece 46 shown in detail in Figure 4 is provided and is disposed at the juncture point of arms 20 and 21. The individual segments 48 and 51 in Figure 4 are 20 insulated from each other by an insulating segment 49 and are so spaced from one another that when the conducting piece 47 at the junction of arms 20 and 21 takes a position such as is shown in Figure 4 and is brought down on any pair of segments, an electrical circuit is established between them which is again interrupted when the conducting piece 47 is raised.

The insulating panel 23 carrying the pairs of segments of which one pair is provided for each circuit to be controlled, and the two arms 20 and 21 are bridged by a yoke 43 which yoke in turn is connected mechanically to a coil 52 movably supported in the magnetic field provided by magnet 53 as shown in Figure 3. When a current of 35 the proper strength traverses coil 52 and in the proper direction the yoke 43 is drawn down and forces the insulated piece 46 carrying conducting member 47 down against the panel 23 at whatever point piece 46 happens to be at the time when 40 coil 52 is energized.

In order to effect this action of yoke 43 the switches 36, 37, 38, 39, 40 and 41 in Figure 3 in addition to having contacts connected to resistances 24, 25, 26, 27, 28, 29, 30, 31, 32, 33, 34 45 and 35 are also each provided with a set of contacts connected in series with coil 52, battery 1 and ground so that whenever any one of the switches 36, 37, 38, 39, 40 or 41 are closed the extra pair of contacts in series with coil 52 is 50 also closed but only subsequent to the closure of the two pairs of contacts connected to the resistors controlled by that switch. By arranging the respective closures in this way, time is allowed for the interconnected pantograph arms to come 55 to rest before piece 47 is depressed to close the circuit between the segments of a pair.

The closure of the circuit between segments of a pair provided by the depression of member 46 can then be used to energize a relay whose contacts are connected in the circuit which it is desired to control. This energization of the circuit in question will continue as long as coil 52 is energized which in practice would mean as long as one of the switches at the transmitter is depressed. As soon as the switch key at the transmitter is released the various circuits at the receiving station will be deenergized and member 46 will be returned to its initial position of rest at the left by spring 92.

It will be noted from a study of the foregoing that the position of member 46 is dependent upon the values of the currents in the two coils 14 and 15. It will also be evident that if the currents to the two coils 14 and 15 should for some reason 75

5 or other suffer a reduction in transmission due to line losses or other causes so that the currents which actually traverse these coils is less than was intended the position of member 46 as a result of the flow of these currents in the actuating coils might not be the one desired which might mean that some other circuit than the one intended would actually be energized at the receiving station.

10 To guard against this possibility a test circuit has been provided which is as follows.

One set of switch contacts is provided at the transmitter which when closed under normal conditions will ensure that member 46 at the receiving station will take some position such as A on panel 23. The two segments of the pair at A may be connected through wires 72, 73, battery 74 and ground to an annunciator or other suitable signaling device at the transmitting station.

20 When the set of switch contacts at the transmitter just referred to above are closed member 46 should move to position A at the receiving station and short circuit the segments of the pair at that point which in turn will energize the coil in the annunciator and show the operator at the transmitter that the system is operating satisfactorily. If the operator at the transmitter does not receive the expected return signal he can then take the necessary steps to locate the cause 30 of the difficulty and correct it.

In all the foregoing description reference has continually been made to the use of pantograph arms at the receiving station and to the use of various resistances at the transmitter to control 35 the actuating current to these arms and consequently the movements of the arms themselves. Although the use of two pantograph arms for controlling the position of member 46 is highly advantageous in a number of cases, it will sometimes happen that a system such as is illustrated 40 in Figure 5 will be sufficient.

In the system illustrated schematically in Figure 5 the pairs of segments which may be short circuited by the conducting piece carried by member 46 are disposed around the arc of a circle whose center is also the axis 101 about which arm 100 is pivoted and free to move under the influence of the force exerted by coil 102 which is movably supported in the field of magnet 103. The arm 100 which supports member 46 is returned to its position of rest at the extreme left by the action of a coil spring or, as in the case shown in Figure 5, may be returned to its position of rest by a combination of a spring and an 55 electromagnet or even by electromagnetic means alone. Rigid member 108 pivoted about axis 104 has one end which may be made arcuate in form so as to ensure that in any position of arm 100 it may be pulled up by the action of magnet 105 60 on armature 106 and thereby depress rigid arm 100 so that conducting member 47 on its outer end may short circuit the desired pair of segments.

Reference to Figure 6 will illustrate the electrical connections of the system where for simplicity sake two points only on the selector have been shown although it will be understood that the number of circuits which can be controlled in this way is by no means so limited. Switches 65 70 75 121 and 122 which are individually capable of selecting one circuit each at the receiver for energization are each provided with two pairs of blades; one being the pair used to introduce the proper resistance into the circuit completed by source of power 120, wires 123 and 124 and mag-

net coil 102 so that arm 100 will assume some desired position at the receiving station, and the other pair of blades being used, after arm 100 has taken up the desired position, to depress arm 100 thereby completing the desired circuit. 5

With reference to the switches used at the transmitter it will be understood that although the foregoing has more particularly referred to the use of switches which will delay the actuation of coil 105 until after arm 100 has reached the 10 desired position, the use of such switches as are illustrated is merely for convenience and that the same result can be obtained by the use of time delay relays connected as shown in Figure 7 to ensure that circuit energization at the receiver will not take place until the individual segments of a pair have been short circuited for the 15 proper length of time.

Under such circumstances as have just been outlined the use of an arm-depressing circuit between the transmitter and receiver can be dispensed with as may also member 108 in Figure 5 and its associated supporting piece together with magnet 105 shown in Figure 8. Figure 7 illustrates the circuit so revised where 125 and 126 20 25 are time delay relays which will not close their respective circuits until the individual segments of the pair of contacts at the receiving station circuit selector with which they are connected in series will have been short circuited for the 30 proper length of time by the short circuiting piece carried on the end of arm 100.

It will be understood that in this particular arrangement the conducting segments of each pair of contacts on the insulating panel 107 (Figure 5) may be made flush with the surface of the panel so that the short circuiting member at the end of arm 100 may be in contact with the surface of the panel at all times and need not be slightly removed from it as would be the case where a 40 depressor mechanism is employed. 35

It will be clear from the foregoing that my invention is of great utility and susceptible to application in a number of different fields which will readily occur to those skilled in the art. 45 For instance the same type of mechanism at the receiving station may be used for controlling purely mechanical operations such as closing or opening valves and the like without departing from the spirit of my invention. In the cases 50 where purely mechanical operations are to be controlled the depression of the arm may be used to effect the operation directly without the intervention of an electrical circuit.

One of the purposes of this invention is to provide a more convenient and simple means for the transmission and reception of so called "teletype" messages wherein typewritten messages can be transmitted to and reproduced at a distant point. Most of the systems now known and in use for 55 this purpose involve the transmission of various impulses or groups of impulses which impulses are used upon their arrival at the receiving station and after passing through a selector mechanism to actuate the keybar carrying the letter or 60 character which it is desired to reproduce.

The best known of these systems is the so called "five unit" teletype where the transmission of any desired letter is effected by transmitting various combinations of impulses and spaces 70 in the "five unit" group. This system while comparatively effective is open to a number of objections among which are that it requires synchronization between the sender and receiver which is frequently difficult to obtain and furthermore 75

that it requires very complicated and expensive apparatus at both the sending and receiving stations.

My invention involves no such difficulties and in fact it can be attached to a standard typewriter without any but minor alterations to the typewriter itself. To learn how this may be done in a simple manner reference should be made to Figure 9 where 1 is a source of power, one side of which is grounded and the other side of which is connected through wire 220 to switch blades 206, 207, 210, 211, 214 and 215. When switch contacts 205 and 206, 209 and 210, or 213 and 214 are closed a current whose magnitude depends on which switch is closed, flows through wires 220 and 221 and thence through coil 218 which is movably supported in the magnetic field provided by magnet 219. This current flow causes coil 218 to move and thereby moves arm 224 to some position over a pair of segments. Closure of contacts 207 and 208, 211 and 212, or 215 and 216 energizes coil 217 and as previously explained depresses arm 224 causing the conducting member at its end to short circuit the segments over which it happens to lie. In the actual equipment two pairs of switch contacts together with an armature are pivotally attached to each key of the typewriter as illustrated in Figure 10 which shows a detail sketch of the keybar and switch contacts 205 and 206, and 207 and 208. When the key is depressed contacts 205 and 206 close first which causes arm 224 to assume some given position determined by the voltage of the source 1 and the resistance 202. Further pressure on the key results in the closure of contacts 207 and 208 which energizes coil 217 and depresses arm 224 and for example if the current in coil 218 is such as to make bar 224 take a position over pair of segments 225, then energizes relay 226. The current caused thereby to flow through coil 227 creates a pull on armature 230 which, acting through rigid member 228 and the short arm of the bell crank typebar 229 pivoted at 232, depresses the typebar and prints the desired letter at the receiving station.

Similar pairs of switch blades are provided for each operation or character which it is desired to transmit. Upper or lower case characters may be transmitted as with the ordinary teletypewriter.

The operation of the carriage shift mechanism is effected in a somewhat different way. The operator at the transmitter upon reaching the end of a line will of necessity operate the carriage return in preparation for the next line. In order to accomplish the same result at the receiving station an extra key is provided at the transmitter with two sets of contact blades similar to the other keys. When this key is depressed the short circuiting member carried on the end of arm 224 short circuits the segments 233 thereby energizing relay 234 and applying power to motor 235 from power supply 238. This motor through the medium of a pinion on its shaft moves rack 236 over and consequently the carriage of the receiving typewriter to its extreme right hand position. A limit switch 237 is provided in series with which is the motor 235 so that the motor will be cut off as soon as it has accomplished the return of the carriage even though the carriage return key at the transmitter may still be depressed.

It will be noted in Figure 10 that a solenoid coil has been provided around the armature on the end of the switch contact bar. It is this coil

which makes it possible to use the same typewriter for transmitting and receiving assuming of course that the movable arm and its associated mechanism and circuits are also provided at the transmitter. When it is desired to make the same machine available for either sending or receiving the coil surrounding the armature on the end of the contact bar in Figure 10 will be connected into the circuit in the position taken by coil 227 in Figure 9. Each of the coils on the remaining keybars will be similarly connected through a relay to a pair of segments on the receiving panel.

It will be immediately apparent that the only remaining equipment required will be a triple-pole double throw switch to throw the equipment from a sending condition to a receiving condition or vice versa with respect to the line wires 221, and 222. A test circuit such as has been described before is also provided consisting of the series circuit made up of annunciator 241, wire 223, source of power 240, contacts 242 and ground.

Direct current circuits such as have been described exclusively in the foregoing are entirely satisfactory for short distance transmission. For longer distances over wire or radio circuits the use of alternating current becomes imperative. My invention is not confined to use on direct current circuits but may with ease be applied to long distance wire or radio circuits equally well.

Figure 11 shows a wiring diagram in sufficient detail to explain the system, of a typical arrangement of my invention for use in transmitting teletype messages over long distance wire or radio circuits. It will be noted that the general arrangement of circuits in the alternating current case is similar in many respects to the direct current cases heretofore discussed except that certain changes which, in order to overcome exigencies inherent in radio circuits, I have found it desirable to incorporate.

Referring to Figure 11 it will be noted that when the double pole switch 307 which is similar in all respects to the key switches shown in Figure 9, is depressed the first action is to allow 1000 cycle current in an amount which is determined by resistor 304 and the voltage of the source, to flow through one of the primary windings of the transformer 308. From thence it may be transmitted by any of the usual wire or radio means to the receiver. At that point it is filtered out by a simple tuned circuit, amplified, rectified and allowed to flow through the windings of coil 318 thereby causing arm 224 to assume some particular desired position with respect to the row of 55 pairs of segments over which it passes. Further pressure on switch 307 causes the other pair of contacts to close which applies a 666 cycle voltage to the primary of transformer 308 which voltage is similarly transmitted to the receiver where it is filtered out, rectified, and applied to coil 217, which results in arm 224 being depressed and the desired circuit at the receiver energized. Arm 224 it will be noted is returned to its position of rest by means of a spring which is secured at one end to arm 224 and at the other end to a coil movably supported in a uniform magnetic field. This coil and the magnetic field in which it is supported are preferably similar to coil 318 and the magnetic field in which it is supported.

A reference to Figure 11 will show that a third source of alternating current is provided having a frequency of 444 cycles the application of which to the primary of transformer 308 is controlled by switch 309.

5 A filter circuit designed to select this frequency to the exclusion of others is provided at the receiver together with an amplifier as shown. When switch 308 is closed a 444 cycle voltage is applied to the primary of transformer 308 and is transmitted to the receiver where it is filtered out, amplified, rectified and allowed to flow through coil 319. In so doing of course it applies a pull to the arm 224 through spring 320 which together with the tension of the spring tends to return the arm 224 to its position of rest. Under ordinary circumstances the tension on the arm produced by this combination will then be made up of two parts; one part being the constant pull of the coil due to the current traversing its windings and the other being the variable tension supplied by the spring which will be a function of the displacement of arm 224 from its position of rest.

20 In ordinary practice the 444 cycle frequency will be transmitted continuously as long as transmissions are to be effected. The number of 666 cycle emissions and the number and intensity of the 1000 cycle emissions will of course depend 25 upon which keys are depressed and how frequently.

The advantage of having one end of the arm return spring attached to the coil which derives its pull from a rectified alternating current received 30 through the same channel as the 1000 cycle current used to control the position of the arm is immediately obvious.

Suppose for instance that the transmission from the sending to the receiving station is effected 35 through a radio circuit. Suppose also that this radio circuit is troubled by static or other disturbances. Since the 444 cycle current, the 666 cycle current and the 1000 cycle current are all transmitted together and filtered out at the receiver, static disturbances received along with the signal affect the 1000 cycle, 666 cycle and 444 cycle circuits nearly equally. Such disturbances will be passed on through the amplifiers, rectified 40 and passed through the two coils 318 and 319 along with the currents from the signals. Any forces set up by the passage of these rectified stray currents through coils 318 and 319 will balance 45 each other out insofar as movement of arm 224 is concerned so that this member is substantially free from interference, within the capacity 50 of the amplifier, due to stray currents.

As will be seen from Figures 8 and 11 a similar plan is used to protect the 666 cycle or depressor circuit from extraneous electrical disturbances, 55 rectified current from the 444 cycle channel being passed through the winding of coil 321 which coil when traversed by rectified stray currents, will provide the necessary force to counterbalance any unwanted movements of the depressor arm when 60 coil 217 is also traversed by rectified stray currents.

The many advantages of my invention will be readily apparent to those skilled in the art. What I claim and wish to secure by Letters Patent is:

1. A method of reducing the effect of extraneous electrical disturbances on electrically controlled mechanical movements consisting of providing at least one voltage, varying this voltage in 70 accordance with the mechanical movement which it is desired to produce, providing a second voltage, transmitting these voltages to a distance, converting them into forces and utilizing the algebraic sum of said forces, at the receiving 75 point to effect the movement desired and to re-

duce the effect on said movement of equal changes in the magnitudes of said forces.

2. A method of determining the accuracy with which mechanical movements are produced at a distance comprising providing a voltage, varying 5 the intensity of this voltage in accordance with a desired movement, transmitting this voltage to a distance, converting it into a mechanical movement at the receiving station and, by the completion of said movement, effecting a notification to 10 the station from which said voltage was transmitted, when said movement coincides with the movement which it is desired to produce.

3. An apparatus for controlling electrical circuits at a distance comprising means for selecting from a plurality of voltages individually adjusted in accordance with circuits which it may be desired to control, a voltage in accordance with the circuit which it is desired to control, means for controlling a second voltage in accordance 20 with the time at which control of the selected circuit is desired, means for transmitting these voltages to a distance, means for converting one of said transmitted voltages into a current and converting said current into a rotatory mechanical 25 movement at the receiving station to effect the selection of the desired circuit and electrically separated means cooperating with the other voltage to effect the control of the selected circuit.

4. A method of controlling electrical circuits at 30 a distance comprising providing a plurality of voltages individually adjusted in accordance with the circuits which it may be desired to control, selecting individually at least one of these voltages in accordance with the circuit which it is 35 desired to control, transmitting it to a distance, converting it into a current and converting said current, while maintaining it constant in direction and magnitude, into a rotatory mechanical movement in accordance with the circuit desired 40 at the receiving point to effect the selection and control of the desired circuit.

5. A method of controlling electrical circuits at a distance comprising providing a plurality of voltages individually adjusted in accordance with 45 the circuits which it may be desired to control, selecting one of these voltages in accordance with the circuit which it is desired to control, transmitting it to a distance, converting it into a current and converting said current, while maintaining it constant in direction and magnitude, 50 into a rotatory circuit completing mechanical movement in accordance with the circuit desired at the receiving station to effect the selection and control of the desired circuit.

6. A method of controlling electrical circuits at a distance comprising providing a plurality of voltages individually adjusted in accordance with the circuits which it may be desired to control, individually selecting at least one of these voltages, transmitting it to a distance, converting it into a current and converting said current, while maintaining it constant in direction and magnitude, 60 into a rotatory mechanical movement at the receiving point in accordance with the circuit desired 65 to effect the selection of the desired circuit and its control a definitely desired time interval thereafter as a result of said selection.

7. A method of controlling electrical circuits at a distance comprising providing a plurality of 70 voltages individually adjusted in accordance with the circuits which it may be desired to control, individually selecting at least one of these voltages in accordance with the circuit which it is desired to control, providing a second voltage, con- 75

- trolling this voltage in accordance with the time at which control of the selected circuit is desired, transmitting these voltages to a distance, converting them into currents and converting the first, while maintaining it constant in direction and magnitude, into a rotatory mechanical movement at the receiving point to effect the selection of the desired circuit and converting the second into an electrically separate electromagnetic control of the selected circuit.
8. A method of transmitting printable characters to a distance comprising providing a plurality of voltages individually adjusted in accordance with the characters which it may be desired to transmit, individually selecting at least one of these voltages in accordance with the character which it is desired to transmit, transmitting this voltage to a distance, converting it into a current and converting said current without change in direction or magnitude into a rotatory mechanical movement at the receiving station in accordance with said current to effect the selection and production of the desired character.
9. An apparatus for controlling electrical circuits at a distance comprising means for selecting from a plurality of voltages individually adjusted in accordance with the circuits which it may be desired to control, at least one voltage in accordance with the circuit which it is desired to control, means for transmitting this voltage to a distance and means for converting it into a current and converting said current, while maintaining it constant in direction and magnitude, into a rotatory mechanical movement at the receiving point in accordance with said current to effect the selection and control of the desired circuit.
10. In an apparatus for controlling electrical circuits at a distance, output terminals, means for selecting from a plurality of voltages individually adjusted in accordance with circuits which it may be desired to control, at least one voltage in accordance with the circuit which it is desired to control, means for delivering it to certain of said output terminals, and means for delivering in accordance with the time at which control of the selected circuit is desired, voltage to other of said output terminals.
11. In an apparatus for controlling electrical circuits at a distance, an input circuit and means associated therewith influenced by current received through said input circuit for effecting the selection of a desired circuit by a rotatory movement in accordance with said current and its control by the unchanged flow in direction or magnitude of said current.
12. In an apparatus for controlling electrical circuits at a distance, an input circuit, an electrical connecting element, and means associated therewith influenced by current received through said input circuit for bringing about a rotatory mechanical movement of said electrical connecting element in accordance with said current to effect the selection of a desired local circuit and its control by the flow unchanged in direction or magnitude of said current.
13. In an apparatus for controlling electrical circuits at a distance, delayed action circuit controlling means, an input circuit, and means associated therewith influenced by current received through said input circuit for bringing about a rotatory mechanical movement in accordance with said current for selecting local circuits in accordance with said current and effecting the control at a definite desired time interval thereafter of the local circuit so selected, through the medium of said delayed action circuit controlling means as a result of said selection.
14. In an apparatus for controlling electrical circuits at a distance, input circuits and means associated with one of said circuits influenced by current received through it for bringing about a rotatory mechanical movement for selecting local circuits in accordance with said current and means electrically distinct from said first means cooperating with and influenced by current received through another input circuit for effecting control of the selected circuit.
15. An apparatus for reducing the effect of extraneous electrical disturbances on electrically controlled mechanical movements, comprising input circuits, means associated therewith for executing mechanical movements in accordance with current received through at least one of said input circuits and means, including a restraining means, cooperating with current received through another input circuit for opposing the movements of said movement executing means so as to reduce the effect on said movement executing means, of equal changes in the magnitudes of the currents received through these two input circuits.
16. In an apparatus for producing printable characters at a distance, typebars, paper feeding means associated therewith, local circuits controlling said typebars, an input circuit and means associated therewith influenced by current received through said input circuit for bringing about a rotatory mechanical movement for individually selecting said local circuits in accordance with said current and controlling said circuits through the flow of said current while it is being maintained constant in direction and magnitude.
17. In an apparatus for effecting the remote control of a typewriter carriage, an input circuit, means associated with said input circuit actuated by current received through it for bringing about a rotatory movement in accordance with said current for selecting and controlling a local circuit and means included in said circuit for effecting the throw of said carriage when said local circuit is completed.
18. In an apparatus for effecting the remote control of a typewriter carriage, an input circuit, means associated with said input circuit actuated by current received through it for bringing about a rotatory mechanical movement in accordance with said current for selecting and controlling a local circuit and means included in said circuit for effecting the throw of said carriage including means for deenergizing said carriage moving means at the completion of the throw, when said local circuit is completed.
19. A method of controlling electrical circuits at a distance comprising providing a plurality of alternating current voltages individually adjusted in accordance with the circuits which it may be desired to control, individually selecting at least one of these voltages in accordance with the circuit which it is desired to control, transmitting it to a distance and converting it into a unidirectional current and converting said current, while maintaining it constant in direction and magnitude, into a rotatory mechanical movement at the receiving point to effect the selection and control of the desired circuit.
20. A method of controlling electrical circuits at a distance comprising providing a plurality of alternating current voltages individually adjusted

5 in accordance with the circuits which it may be desired to control, individually selecting at least one of these voltages in accordance with the circuit which it is desired to control, providing a second alternating current voltage of a different frequency, controlling this voltage in accordance with the time at which control of the selected circuit is desired, transmitting these voltages to a distance and converting them into unidirectional currents and converting said currents into electrically distinct mechanical movements at the receiving point to effect the selection and control of the desired circuit.

10 21. A method of controlling electrical circuits at a distance comprising providing a plurality of alternating current voltages individually adjusted in accordance with the circuits which it may be desired to control, selecting one of these voltages in accordance with the circuit which it is desired to control, transmitting it to a distance and converting it into a unidirectional current and converting said current into a circuit completing rotatory mechanical movement at the receiving station to effect the selection and control of the desired circuit.

15 22. A method of transmitting printable characters to a distance comprising providing a plurality of alternating current voltages individually adjusted in accordance with the characters which it may be desired to transmit, individually selecting at least one voltage in accordance with the character which it is desired to transmit, transmitting this voltage to a distance and converting it into a unidirectional current and converting said current into a rotatory mechanical movement at the receiving station to effect the selection and production of the desired character.

20 23. An apparatus for controlling electrical circuits at a distance comprising means for selecting from a plurality of alternating current voltages individually adjusted in accordance with the circuits which it may be desired to control, at least one alternating voltage in accordance with the circuit which it is desired to control, means for transmitting this voltage to a distance and means for converting it into a unidirectional current and converting said current without change in direction or magnitude into a rotatory mechanical movement at the receiving point to effect the selection and control of the desired circuit.

25 24. In an apparatus for controlling electrical circuits at a distance, an input circuit adapted to the receipt of alternating current voltages, means for converting said voltages into unidirectional currents in accordance with said voltages, an electrical connecting element, and means associated therewith influenced by said unidirectional current received through said input circuit for

bringing about a rotatory mechanical movement of said electrical connecting element to effect the selection of a desired local circuit and its control.

25 25. In an apparatus for reproducing printable characters at a distance, typebars, paper feeding means associated therewith, local circuits controlling said typebars, an input circuit adapted for the receipt of alternating current voltages, means for converting said voltages into unidirectional currents in accordance with said voltages and means associated with said unidirectional currents influenced thereby for bringing about a rotatory movement for individually selecting said local circuits in accordance with said current and controlling said circuits by said current.

30 26. A method of transmitting printable characters to a distance comprising providing a plurality of voltages individually adjusted in accordance with the characters which it may be desired to transmit, individually selecting at least one of these voltages in accordance with the character which it may be desired to transmit, providing another voltage, controlling this voltage in accordance with the time at which reproduction of the selected character is desired, transmitting these voltages to a distance, converting them into currents and converting said currents into electrically separate mechanical movements at the receiving point to effect the selection and reproduction of the desired character.

35 27. A method of transmitting printable characters to a distance comprising providing a plurality of voltages individually adjusted in accordance with the characters which it may be desired to transmit, individually selecting at least one of these voltages, transmitting it to a distance, converting it into a current and converting said current into a rotatory mechanical movement at the receiving point in accordance with the character desired to effect the selection of the desired character and its reproduction a definitely delayed time interval thereafter as a result of said selection.

40 28. In an apparatus for controlling electrical circuits at a distance, an input circuit adapted to the receipt of an alternating current voltage, means for converting said voltage into a unidirectional current means associated with said unidirectional current and influenced by it for bringing about a rotatory mechanical movement for effecting the selection of the desired circuit in accordance with said current and its control by the flow of said current while it is being maintained constant in direction and magnitude.

45 PHILIP NORMAN SMITH.
